UNITED STATES PATENT OFFICE.

HENRY LUMSDEN WOOLFENDEN AND CLIFFORD WAYNE HUMPHREY,
OF DENVER, COLORADO.

SIGN.

SPECIFICATION forming part of Letters Patent No. 781,859, dated February 7, 1905.

Application filed September 10, 1904. Serial No. 224,046.

To all whom it may concern:

Be it known that we, HENRY LUMSDEN WOOLFENDEN and CLIFFORD WAYNE HUMPHREY, of Denver, Colorado, (whose post-office addresses are 435 Seventeenth street, Denver, Colorado,) have invented certain new and useful Improvements in Signs, of which the following is a specification.

Our invention relates to movable or variable signs in which the sign or relative portions of certain elements thereof may be moved either intermittently or continuously, as desired. The movement of the parts of the sign may advantageously be made to vary their shape or contour in some instances and may also vary the contour of letters, borders, or other characters or representations thereon. When such letters, borders, or the like are outlined in incandescent lamps or other light-distributing elements, the effect is particularly striking.

Figures 1 and 2 of the drawings represent, in side elevation, a sign embodying our invention in two of its varied positions. Fig. 3 shows a modified form of sign in two positions. Fig. 4 shows in two positions a further modification. Figs. 5 and 6 show further modifications of our invention. Figs. 7 and 8 show in two positions still different forms of the device.

Referring to Figs. 1 and 2 of the drawings, 11 designates a wall or like support from which extends a horizontal rod or pole 12. From the pole 12 depends a plurality of frames, (shown as three in number and designated as 21 22 23, respectively.) Each of these is shown as consisting of a plurality of bars 24, all pivoted at each of their ends to cross-bars 25, so that the entire frame may be racked to produce a "diamond-shaped" figure, with its longer axis either horizontal or vertical. On each of the frames may be outlined a letter or other character. We have shown for the purpose of illustration only certain letters formed of a plurality of light-giving elements, as electric-light bulbs 26, in a well-known manner.

It will be seen that one or more of the bulbs is secured to each of the bars 24, and it is evident that any well-known form of reflector may be employed for each bulb or that a space at the base of each bulb may be given a dis-

tinctive, preferably light-reflecting, color, as is customary in the art, or the bulbs may be omitted or removed without entirely destroying the efficiency of the device. As shown, the frames 21 22 23 are ornamented with bulbs 55 forming the letters G, A, and S, respectively. The frame 23 farthest from the wall 11 is shown as secured to the rod 12 at its upper corner, the frames 21 and 22 as hung on idlers to freely move along the rod, and all the frames 60 as having pivotal connections 27 at their adjacent corners. A rod 28 is secured to the frame 21 and extends to any source of motion which may be within the building represented by the wall 11. It is evident that the retraction of the rod 12, as shown in Fig. 1, horizontally elongates the frames 21 22 23, whereby the letters thereon assume a low broad shape. When the rod 12 is protruded, as in Fig. 2, the frames are elongated vertically 70 and the letters correspondingly distorted without in this case losing their identity or legibility.

Fig. 3 shows in two positions a variably-shaped box-like frame 31, which may be supported from one of its corners and distorted in either direction from the cubical form. As the means by which its shape is altered form no part of our present invention and are within the province of a skilled mechanic, we have 80 not deemed it necessary to particularly illustrate or describe them. It is clear that, as before, the movement of the frame 31 distorts the letters 32 or the like outlined on its sides.

In Fig. 4 we represent a panel 41, shown 85 as of annular form, on which may be represented any desired device for advertising or like purposes. The matter on the panel 41 is lighted by a plurality of electric bulbs 42, secured to the frame composed of bars 43, pivoted together at their ends and provided with guiding-rods 44, shown as sliding behind the panel 41, and a part 45, to which the movement-producing device (not shown) may be attached.

In Fig. 5 is shown the wall 11 and pole 12 of Fig. 1. From the pole depends by means of an extension device 51 of the well known "pantograph" or "lazy-tongs" pattern a sign 52, which may be of any desired configuration 100

and may be electrically lighted, as shown. The outer upper corner of the lazy-tongs 51 is secured to the pole 12 and the inner upper corner to a rod 28, as above described. 5 It is evident that the longitudinal movement of the rod 28 will alternately raise and depress the sign 52.

The form of our device shown in Fig. 6 provides a plurality of telescoping frames 61 62 10 63 64, the number of which may of course be increased or decreased, as desired. The frame 61 is shown as secured to a wall 11 and as of a size and shape to inclose or practically to conceal the frame 62, on which is a letter, 15 figure, or other part of a sign or similar device. In like manner the frame 62 is adapted to receive or cover the frame 63, containing any portion of the sign. This in turn may hide the frame 64. A lazy-tongs 65 connects the frames and by means of the longitudinal movement of the rod 28 alternately reveals the lettered frames, as shown in the drawings, or retracts them behind or within the frame 61. It is clear that by suitable 20 mechanism the different frames may be caused to emerge in any desired order.

Fig. 7 of the drawings shows two positions of a further modification of our invention. In this case the wall 11 carries a sign 71, which 30 may be formed of or illuminated by lamps 72. Adjacent the sign 71 is a horizontally-disposed extension device 73, opened and closed by a rod 28, as before. The outer bars 74 75 of the extension device 73 are formed 35 to receive a vertical rod 76, which may bear on its upper end a pointer 77, shown as a hand. The upper end of the rod 76 is twisted or otherwise formed to a thread of high pitch, so that the extension of the tongs 73 serves to 40 rotate the pointer 77. The parts are preferably so arranged that the hand when fully extended points toward the sign 71. Obviously the hand may be self-illuminated in any 45 advantageous manner.

Fig. 8 represents varied positions of a device formed of upper and lower hoops 81 82, connected by a plurality of pivotally-attached 50 staves or bars 83. The hoops and bars may bear as light-distributing elements 84 either electric bulbs or light-reflecting jeweled ornaments, as preferred. Means (not shown) for rotating either or both of the hoops on its 55 axis serve to vary the contour of the device from a cylinder to the hour-glass form shown.

We have illustrated and described several 60 different forms of our invention to indicate that we do not wish to be limited to a particular construction. It is also evident that the material, as well as the configuration of the device, may vary within wide limits.

Having thus described our invention and without limiting ourselves to details, what we claim as new therein, and desire to secure by Letters Patent, is—

65 1. A sign or advertising device consisting

of a plurality of pivotally-connected parts, and means for producing a relative motion of said parts on their pivots, whereby the configuration of said parts is alternated.

2. A self-illuminated sign or advertising device 70 comprising a plurality of pivotally-connected parts, and means for producing a relative motion of said parts on their pivots, whereby the configuration of said parts is alternated. 75

3. A sign or advertising device composed of a plurality of parts, each of which comprises a letter or character, and means for producing a relative motion of said parts whereby the configuration of said parts is alternated. 80

4. A sign or advertising device comprising a plurality of parts, each having a plurality of light-distributing elements, and means for producing a relative motion of said parts whereby the configuration of said parts is alternated. 85

5. A sign or advertising device comprising a plurality of parts, each bearing a plurality of light-distributing elements, means for varying the relative position of said parts, and 90 means for varying the relative positions of said elements with respect to the part on which they are supported.

6. A sign or advertising device comprising a plurality of parts, each bearing a plurality 95 of light-distributing elements, and synchronously-operating means for varying the relative position of said parts and for varying the relative positions of said elements with respect to the part on which they are supported. 100

7. A sign or advertising device comprising a plurality of parts, each bearing a plurality of light-distributing elements forming a letter or character, means for varying the relative position of said parts, and means for varying the relative positions of said elements with respect to said parts, whereby said letters or characters are distorted. 105

8. A sign or advertising device comprising a frame consisting of a plurality of pivotally-connected bars bearing portions of a letter or character, and means for varying the contour of said frame, whereby the contour of said letters is distorted. 110

9. A sign or advertising device comprising 115 a plurality of frames, each composed of a plurality of pivotally-connected bars bearing portions of a letter or character, means for varying the relative positions of said frames, and means for varying the contour of said frames, 120 whereby the letters or characters thereon are distorted.

In testimony whereof I have signed this specification in the presence of two subscribing witnesses.

HENRY LUMSDEN WOOLFENDEN,
CLIFFORD WAYNE HUMPHREY.
